United States Patent

Des. 235,809
Patented July 8, 1975

235,809

WALKER

Morton I. Thomas, Bakertown Road,
Monroe, N.Y. 10950

Filed Apr. 9, 1973, Ser. No. 349,053

Term of patent 14 years

Int. Cl. D3—03

U.S. CL. D88—1

FIG. 1

FIG. 3

FIG. 2

FIG. 4

FIG. 6

FIG. 5

FIG. 1 is a perspective view of a walker showing my new design;

FIG. 2 is a side elevational view thereof;

FIG. 3 is an end elevational view thereof;

FIG. 4 is a perspective view of a modified form of the design in FIG. 1;

FIG. 5 is a side elevational view of the modified form; and

FIG. 6 is an end elevational view of the modified form. I claim:

The ornamental design for a walker, substantially as shown and described.
